UNITED STATES PATENT OFFICE.

EUGENE J. WITCHGER, OF SAGINAW, MICHIGAN, ASSIGNOR TO LUFKIN RULE CO., OF SAGINAW, MICHIGAN, A CORPORATION OF MICHIGAN.

TAPE REEL.

Application filed March 18, 1925. Serial No. 16,317.

This invention relates to tape reels of the well known double-bearing drum type, characterized by a tape drum journaled at both ends, as distinguished from a drum 5 journaled wholly in one side of the case.

More specifically my invention is an improved frictioning means that prevents undesirable spinning of the drum when the tape tends to back lash, yet does not interfere with the normal operations of winding and unwinding.

My improved frictioning device has certain novel features, important from a standpoint of durability in use and noteworthy 15 absence of shakiness in the drum mechanism, and as regards rapid and economical manufacture and assembling.

I take a double-bearing tape reel of usual construction and insert between the bottom 20 wall of the case and the drum a suitable resilient member, as a spring or its equivalent. By being introduced at this location in the mechanism, the spring member causes the drum to function in a novel manner and 25 enables me to attain the objects of my invention.

The objects are, to provide a simple drum frictioning device adapted to be easily applied and renewed in existing types of 30 double-bearing tape measures; to produce a device which, placed at the bottom part of the case will so operate as to eliminate wear at the top drum flange and at the top wall bushing. It also prevents end play of the 35 drum. A further object is to enable friction faces of large area to be employed and to be so arranged as not to interfere with inserting the drum into the case. These results are secured by the addition of a single inexpensive element and without materially 40 altering the construction of the drums now in common use.

With the foregoing and certain other objects in view which will appear later in the 45 specifications, my invention comprises the devices herein described and claimed and the equivalents thereof.

Fig. 1 is a part sectional view of a tape measure embodying my improvement, a 50 preferred form of frictioning device being shown diagrammatically.

Fig. 2 is a similar view illustrating a modified form of spring, the flange-screw and washer detached.

55 Figs. 3 and 4 are respectively a plan and

side view of a spring of the kind indicated in Fig. 1.

Fig. 5 is a plan view of the spring structure of Fig. 2, distorted as to thickness.

As is clearly shown in the drawings, 60 numeral 1 indicates the usual tape drum with its flange 2 and post 3. A bushing 4 in the top wall of the case serves as a journal bearing for the cylindrical shell of the drum when winding and unwinding.

A smaller bushing 5 in the bottom wall of the case forms a journal bearing for the projecting end of the drum post 3. Drums so supported are designated as "double-bearing."

A flange or screw head 6 and renewable washer 7 are secured to the projecting end of post 3 to keep the drum in place.

My invention is particularly concerned 75 with the above mentioned features of double-bearing drum tape measures. As heretofore made such tape measures generally had disadvantages, namely, a tendency to drum spinning when the tape was tensioned and then released; frictional wear between the 80 flange 2 and the bushing 4; end play of the drum, causing shakiness.

Inspection of Figs. 1 and 2 shows that the amount of actual drum end play is determined by the distance between the inner 85 faces of flange 2 and washer 7, compared with the distance between the outer faces of bushings 4 and 5. Consequently, even though the case and mechanism be accurately constructed, rough usage such as denting the 90 case may either increase or decrease the original end play and thereby either produce disagreeable rattling or else cause binding and consequent wear of the top bushing and the inner face of drum flange 2.

95 My present improvement overcomes the foregoing objections.

In its broader aspect the invention comprises an expandable or resilient member such as a spring, concealed within the case 100 and positioned to exert a yielding or cushioning effect that normally urges the tape drum lengthwise away from the bottom wall of the case, as indicated at S, Fig. 1.

The top flange 2 of the drum is thereby 105 kept normally separated from the outer face of bushing 4 in the top wall, consequently wear that has heretofore occurred at that place is eliminated.

The spring may be of any suitable con-

struction, although I prefer that shown in Figs. 1 and 3. A washer-like body 8 with radially disposed, downwardly and outwardly bent spring leaves 9 is placed on the post 3, which is suitably shouldered as at 10 to receive it. The free ends of the leaves preferably bear upon the bottom wall of the case and slide frictionally thereon when the drum rotates in either direction.

10 A modified spring structure is shown in Figs. 2 and 5, where a circular sheet metal band 11 is received in and fits the inner periphery of the drum 1. Spring legs 12 are carried by the band 11 and have friction faces that bear against the bottom wall of the case. The mode of operation is the same with both forms of spring.

End play of drum 1 relative to the case is prevented by any suitable spring member 20 action in location S, Fig. 1, because the spring holds the flange or screw head 6, at the projecting end of the drum post 3, snugly against the outer face 5 of the bottom wall bushing. So arranged, there is no likelihood of binding even though the walls of the case become somewhat bent or dented after long use.

When applied either to the drum 1 at its bottom end, as in Fig. 2, or to the drum post 3, as in Fig. 1, the spring member enables large friction faces to be used without extending the ends of the spring beyond the circle of the drum rim, as in earlier constructions.

35 My construction enables the drum and its associated working parts, including the spring to be installed in the reel case without special skill or manipulation, and about as quickly as is possible with tape measures 40 of the usual double-bearing drum type, but lacking this improved frictioning device.

Special operations on the drum rim, such as slotting or perforating to accommodate a frictioning spring, are no longer necessary.

45 In winding and unwinding tape measures the drum revolves and the case does not. It is, therefore, obvious that any suitable resilient member operatively located to exert yielding thrust between the drum and the bottom wall of the case, and adapted to accomplish the purpose of my improvement with respect to frictioning and avoidance of wear etc., as set forth herein, may fall within the scope of my invention as claimed, whether the spring member is made to turn with the drum and rub on the bottom of the case or vice versa.

By applying the resilient compression

member or spring to operate against the bottom wall I have secured results that as far as I am aware have not heretofore been attained. The drum is frictioned against back-lashing and end play is avoided, while wear on the drum flange is entirely prevented. The wear is taken by the renewable washer 7 and the frictioning surfaces of the spring, both of which are readily replaceable.

Having thus described my invention, what I claim and desire to secure by Letters Patent is:

1. In a tape measure having a case comprising a bottom wall and a top wall, a tape drum free to move lengthwise a limited distance and having a flange adjacent the exterior of said top wall, means to prevent the entire removal of the drum, a resilient member located between the drum and said bottom wall, adapted to force the flange away from the top wall.

2. In a tape measure having a case comprising a bottom wall and a top wall, a drum-supporting bearing in each wall, a tape drum rotatably mounted in said bearings and free to move lengthwise a limited distance and having a flange adjacent the exterior of said top wall, means to prevent the entire removal of the drum, a resilient member, located between the drum and said bottom wall, adapted to force the flange away from the top wall.

3. In a tape measure of the type specified, having a top wall, a bottom wall, bearings in said walls, a drum free to move lengthwise a limited distance, rotatably mounted in said bearings and having a flange adjacent the exterior of said top wall, means to prevent the entire withdrawal of said drum, said means engaging the exterior of the bottom wall, a resilient member located between the drum and said bottom wall, for the purposes set forth.

4. In a double-bearing tape measure including a bottom wall and a drum provided with a top flange and a drum post having a flange thereon engaging an outer face of said bottom wall, a spring drum-frictioning member operatively interposed between the bottom wall and the drum and adapted to urge the drum away from the bottom wall and to yieldingly hold said drum post flange in contact with the outer face of said bottom wall, whereby to prevent wear of the top flange of the drum.

In testimony whereof, I affix my signature.

EUGENE J. WITCHGER.
